UNITED STATES PATENT OFFICE

JOHN CLIFFORD WHITRIDGE AND HARRY H. WOLFE, OF COLUMBUS, OHIO, ASSIGNEES
TO THE BUCKEYE STEEL CASTINGS COMPANY, OF COLUMBUS, OHIO

CAR TRUCK

Application filed September 12, 1929. Serial No. 392,234.

This invention relates to improvements in car trucks, and the primary object of the invention is to improve such trucks to permit them to be used on tracks of different gauges.

It is known that all railways do not have tracks of standard gauge, and in Australia particularly, the railways are government owned, and the various States have tracks of different gauges. Passengers and freight must be transferred at the State line. This inconvenience is of course realized, and a commission was appointed to investigate this condition, and it was decided to standardize on the 4' 8½" gauge track. The change over will take some time, and the intention now is to build the trucks, for cars running on the wider gauges, so that they may be also used on the narrower gauge.

It was originally proposed to design axles so that the wheels could be moved in far enough to fit the standard gauge. This arrangement would increase the distance from the center line of the axle journal to the center line of the wheel considerably, and would necessitate a reduction in the loading of the car.

We propose to replace the present axles with new ones, but still maintain the present relation between the center line of the axle journal and the wheel. In order to do this, the bolster must be specially designed to allow the side frames of the truck to be moved in the same amount as the wheels.

Therefore, another object of this invention is to provide a bolster which may be readily adapted for either narrow or wide gauge tracks, and which will properly cooperate with the truck side frames, regardless of whether the truck is used for one gauge tracks or another.

With the foregoing objects outlined and with other objects in view which will appear as the description proceeds, the invention consists in the novel features hereinafter described in detail, illustrated in the accompanying drawings, and more particularly pointed out in the appended claims.

Referring to the drawings,

Fig. 1 is a side elevation of a portion of

a car truck with the wheels shown in dot and dash lines.

Fig. 2 is a top plan view of a portion of the same.

Fig. 3 is a side elevation of one end portion of our improved bolster with the filling blocks omitted. 55

Fig. 4 is a top plan view of the same, with the column fillers shown in dotted lines.

Fig. 5 is an elevation of one of the column fillers. 60

Fig. 6 is an end view of the same.

Figs. 1 and 2 show portions of a known truck which is illustrated for the purpose of disclosing the invention. This truck comprises two side frame members 7, (only one of which is shown), supported by wheels 8 which travel on the railway tracks. Each side frame has columns 9 that are spaced apart by a bolster opening 10 in which an end 11 of the bolster is supported by coil springs 12. Lugs 12a project from opposite sides of the bolster at each end thereof, and they embrace the columns 9 for interlocking the bolster with the side frames. Obviously, the lugs 12a restrict lateral movement of the side frames, and consequently, the ordinary bolster of the type shown in Figs. 1 and 2 will prevent the side frames being used with longer or shorter axles. 65 70 75 80

In accordance with our invention, as shown in Figs. 3 to 6 inclusive, 13 is a bolster of the usual type having inside column guides 14 arranged for use on the standard gauge, and outside column guides 15 arranged for use on the wider gauge. The distance X in Fig. 4 between the two column guides or lugs, is ordinarily only slightly greater than the width of the frame columns, as shown in Fig. 2, but in our present invention, this distance is increased by one-half the difference in the gauges of track, and the vertical faces 16 at the opposite sides of the bolster are pierced by pairs of apertures 17 to receive rivets that are used in fastening the column filler 18 against either the lugs 14 or the lugs 15, as indicated in dotted lines in Fig. 4. Of course, each column filler, like the bolster, is made of metal, and is provided with two apertures 19, corresponding to either pair of the 85 90 95 100

apertures 17. The column filler castings are fastened to the bolster to reduce the dimension X to slightly greater than the width of the frame columns.

5 When this new type of bolster is used on a truck for the wide gauge track, the side frames will be in the outermost position, and the column fillers 18 will be fastened to the bolster against the lugs 14. On the other hand, when the bolster is used on a truck for the standard gauge track, the frames will be in their innermost position, and the column filler castings will be fastened to the bolster so as to abut against the lugs 15.

15 From the foregoing description, it will be clear that we have provided a novel bolster which may be readily adapted to accommodate trucks to be used either on a wide gauge track or a standard gauge track, and this without unduly spacing the center line of the axle journal away from the center line of the wheel.

20 It is believed from the above description that the construction, operation and advantages of the invention may be readily understood by those skilled in the art, and we are aware that changes may be made in the details disclosed, without departing from the spirit of the invention, as expressed in the claims.

25 What we claim and desire to secure by Letters Patent is:

30 1. In a car truck, a side frame having columns arranged at opposite sides of a 35 bolster opening, a bolster end extending into said opening, and having lugs overlapping the columns, and fillers arranged between only one of the outer side surfaces of the columns and certain of said lugs.

40 2. In a car truck, a side frame having columns arranged at opposite sides of a 45 bolster opening, a bolster end extending into said opening and provided with oppositely projecting pairs of guide lugs, the distance between the lugs of each pair being greater than the width of either one of the columns, and fillers on the bolster arranged between the columns and certain of said lugs.

45 3. In a car truck, a side frame having 50 columns arranged at opposite sides of a bolster opening, a bolster end extending into said opening and provided with oppositely projecting pairs of guide lugs, the distance between the lugs of each pair being greater than the width of either one of the columns, fillers on the bolster arranged between the columns and certain of said lugs, and means 55 for securing the fillers to the bolster.

60 4. In a car truck, a side frame member 65 having columns arranged at opposite sides of a bolster opening, a bolster end extending into said opening and provided with pairs of oppositely projecting lugs overlapping the columns, the distance between the lugs of 65 each pair being greater than the width of

either one of said columns, and metal filler blocks fastened to the bolster and arranged between the columns and certain of said lugs.

5 In an adjustable car truck, a bolster having an end provided with pairs of oppositely projecting lugs, and means on the bolster to permit a filler block to be attached to either side of the bolster and in abutting relation with any one of said lugs.

10 6. A bolster for use with an adjustable car 75 truck, provided at one end with pairs of oppositely projecting lugs, the sides of the bolster being apertured adjacent to each of said lugs to facilitate the attachment of 80 filler blocks to the bolster.

7. In a car truck, a side frame member 85 provided with columns arranged at opposite sides of a bolster opening, a bolster member extending into said opening and provided with pairs of oppositely projecting lugs overlapping the columns, and fillers secured to one of said members and arranged between the columns and certain of said lugs.

8. In a car truck, a side frame having 90 columns arranged at opposite sides of a bolster opening, a bolster end extending into said opening and having lugs overlapping the columns, and fillers mounted on the bolster and arranged between the columns and certain of said lugs.

95 9. In testimony whereof, we have signed this specification.

JOHN CLIFFORD WHITRIDGE.
HARRY H. WOLFE.
